(57) **CLAIM**

The ornamental design for a recycle bin system, as shown and described herein.

DESCRIPTION

FIG. 1 is a side perspective view of a recycle bin system in accordance with the present invention, the recycle bin system in receipt of an exemplary pair of bins and an exemplary roller;

FIG. 2 is a side elevation thereof;

FIG. 3 is a front elevation thereof;

FIG. 4 is a rear elevation thereof;

FIG. 5 is a top plan view thereof; and,

FIG. 6 is a bottom plan view thereof with the exemplary roller.

The broken and dashed lines in FIGS. 1-6 are for illustrative purposes only and form no part of the claimed invention.
